Primary Examiner — David G Muller*Assistant Examiner* — Jamaal Rasheed(74) Attorney, Agent, or Firm — Stratford Group Ltd.(57) CLAIM

The ornamental design for a crescent grab bar, as shown and described.

DESCRIPTION

FIG. 1 is a perspective view of the crescent grab bar showing our new design;

FIG. 2 is a top plan view thereof; The bottom view being a mirror image of that shown;

FIG. 3 is a right view thereof;

FIG. 4 is a front elevation view thereof;

FIG. 5 is a left view thereof; and,

FIG. 6 is a rear elevation view thereof.

The broken lines in the drawings depict portions of the crescent grab bar that form no part of the claimed design.
